UNITED STATES PATENT OFFICE

123,690

DESIGN FOR A COMBINED GAME CHIP RACK AND ASH TRAY OR THE LIKE

Charles Cruze, Los Angeles, and Albert G. Babo, South Pasadena, Calif.

Application August 19, 1940, Serial No. 94,507

Term of patent 7 years

To all whom it may concern:

Be it known that we, Charles Cruze and Albert G. Babo, citizens of the United States, residing, respectively, at Los Angeles and South Pasadena, in the county of Los Angeles, State of California, have invented a new, original, and ornamental Design for a Combined Game Chip Rack and Ash Tray or the like, of which the following is a specification, reference being had to the accompanying drawing, forming a part thereof.

Fig. 1 is a perspective view of the combined game chip rack and ash tray or the like, showing our new design;

Fig. 2 is a front elevational view thereof; and
Fig. 3 is an end elevational view thereof.

We claim:

The ornamental design for a combined game chip rack and ash tray or the like, substantially as shown.

ALBERT G. BABO.
CHARLES CRUZE.
